POINTER, UNDERLINER, AND WEIGHT

Filed July 19, 1930

Halden R. Thoresen

INVENTOR

William Thompson
WITNESS:

Victor J. Evans
ATTORNEY

UNITED STATES PATENT OFFICE

HALFDAN R. THORESEN, OF BROOKLYN, NEW YORK

POINTER, UNDERLINER, AND WEIGHT

Application filed July 19, 1930. Serial No. 469,158.

My present invention relates to a new and novel desk implement and has for its object to produce an implement or device which may be used with equal facility as a paper cutter, a straight edge, a paper weight, a pointer, a scale or an underliner, that is, as a device to aid in underlining numbers when using an adding machine or underlining lines in reading or copying to relieve eye strain.

10 To the attainment of the foregoing the invention consists in the improvement herein-after described and definitely claimed.

In the drawings:

Figure 1 is a perspective view of the improvement.

Figure 2 is an approximately central transverse sectional view therethrough.

Figure 3 is an end elevation.

Figure 4 is a plan view looking toward the under face of the improvement.

Figure 5 is a sectional view approximately on the line 5—5 of Figure 2.

Figure 6 is a perspective view of a weighted pointer.

25 The central portion and what I will term the body of my improvement is in the nature of a block of any desired material, wood preferred. The block has its rear portion round in plan, as indicated by the numeral 1, its sides slightly concaved, as at 2, whereby the block can be readily gripped and handled. The block from its lower flat face is formed with a somewhat reduced extension 3, the upper face of the said extension being cut at an

35 angle, as indicated by the numeral 4. The sides of the extension, in a line with the angle face thereof are provided with grooves 5 and the said angle face of the extension, adjacent its juncture with the body is provided with a

40 rounded depression 6 and at its juncture with the body with a lip 7 whose outer end overlies the outer portion of the angle surface 4 and the block at the sides of the lip with depressions 8. The rounded body portion 1 of

45 the block, from its under face, is formed with a depression or pocket for a weight such as lead 9 and whereby the block will be firmly supported when arranged upon a flat surface.

50 The block provides the pointer of the improvement, and when used alone affords a

marker whereby a clerk or student may check up on words or figures by gripping the body of the block and arranging the pointed end thereof under the word or figure desired so that the same can again be referred to without loss of time. In addition to this the device may be employed as a paper weight.

55 The blade which is removably secured to the block is preferably in the nature of a steel plate and is indicated by the numeral 10. The plate has its outer edge straight and is provided with a rule or like scale 11. The rear edge of the plate 10 is rounded downwardly upon itself, as at 12, and from the center of the plate is notched or otherwise cut-

away, as at 13. Slightly inward of the end walls provided by the notches the under face of the plate is formed with inwardly directed ribs 14 and these ribs are designed to be received in the grooves 5 when the plate is applied.

50 The body of the plate, at the center thereof is slotted to provide the same with a downwardly rounded spring tongue 15 designed to be received in the depression 6 in the extension of the block when the plate is arranged upon the beveled face 4 of the said extension 3. When the plate is applied the improvement may be employed as an underliner, that is, the same may be arranged

70 beneath a line of words or figures and through the medium of the weighted block will be sustained proper positioned. The device when the plate is arranged thereon is an effective aid in underlining numbers in an

75 adding machine leaving only the numbers wanted and the ones checked in sight. The plate 10 affords the device with a rule, a paper cutter, a means whereby paper may be torn around the outer edge thereof as well

80 as a scale and it is thought that the foregoing description will fully and clearly set forth the construction and simplicity of the improvement to those skilled in the art without further detailed description. Obviously I do

85 not wish to be restricted to the precise details herein set forth and, therefore, hold myself entitled to make such changes therefrom as fairly fall within the scope of what I claim.

Having described the invention, I claim:

1. In a device for the purpose set forth, a

- weighted block having a rear portion which is round in plan, its sides grooved inwardly and one of its faces formed with an extension whose upper face is arranged at an angle and whose sides are grooved, the upper face of the block, at the juncture of the extension thereof, being formed with an extending lip having depressions to the sides thereof, and outward of the lip being formed with a rounded depression, a blade, having its outer edge provided with a scale, its inner edge rounded, its center cut away from its said inner edge, its under face formed with inwardly directed ribs designed to be received in the grooves of the block extension and an arched spring tongue on said plate adapted to be received in the rounded depression in the block extension for removably holding the plate on the block.
- 20 2. In a device for the purpose set forth, a weighted block having an extension on one face thereof whose outer surface is cut at an angle and provided with a concaved depression, said block having a lip extending over the angle extension, a blade having an inner rounded edge centrally cut-away to receive the block therein, and to underlie the finger of the block and a spring tongue on the blade to be received in the depression on the angle surface of the block extension.

In testimony whereof I affix my signature.
HALFDAN R. THORESEN.
